UNITED STATES PATENT OFFICE.

WALTER JAMES RUSSELL, OF WINNIPEG, MANITOBA, CANADA.

GRAIN-ROASTING DRUM.

Application filed March 13, 1924. Serial No. 699,141.

To all whom it may concern:

Be it known that I, WALTER JAMES RUSSELL, a subject of the King of Great Britain and resident of the city of Winnipeg, in the

Province of Manitoba, Canada, have invented certain new and useful Improvements in Grain-Roasting Drums, of which the following is the specification.

The invention relates to improvements in roasting drums and particularly to drums for roasting all classes of grain, rye or barley, including barley malt and caramel malt and an object of the invention is to provide means in the drum for stirring the grain within the drum so that the same will be evenly roasted, and to construct the stirring means such that it can be readily introduced into existing drums and at comparatively small expense.

With the above more important objects in view the invention consists essentially in the arrangement and construction of parts hereinafter more particularly described, reference being had to the accompanying drawings in which:

Fig. 1 is a plan view of a grain roasting apparatus and showing my invention installed in the drum thereof.

Fig. 2 is an enlarged detailed vertical sectional view at 2-2' Fig. 1.

Fig. 3 is vertical sectional view at 3-3' Fig. 2.

Fig. 4 is a horizontal sectional view at 4-4' Fig. 2 and looking downwardly.

In the drawings like characters of reference indicate corresponding parts in the several figures.

The roasting drum 1 is of the ordinary type being spherical in shape and provided with diametrically opposing doors or gates 2 and 3 such permitting of the insertion and removal of the grain treated in the drum. The drum is rotatably supported so that it can be revolved at comparatively high speed around a longitudinal axis positioned at right angles to the axis of the outlet openings 2 and 3, and it is further mounted so that it can be bodily swung in the horizontal plane ninety degrees or thereabouts in order to bring the drum over a heater.

In order that the invention may be more fully understood I will now give a short description of the drum mountings and other parts associated therewith.

To the side of the drum an upright post 3^a 55 is located and on this post a sleeve 4 is rotatably mounted, the sleeve providing a passage 5 around the post which communicates with a pipe 6 which opens through a cap 7 to the interior of the drum, the cap being permanently secured to the side of the drum and rotating in the upper end of the pipe. A driving shaft 8 is secured to the side of the drum and extends through the cap and the upper end of the pipe into a bearing sleeve 60 9 formed integral with the upper end of the pipe. The outer end of the shaft 8 is fitted with a bevel gear 10 which meshes continuously with a bevel pinion 11 rotatably mounted on the post. The gear 11 is provided with under teeth 12 which engage with a bevel pinion 13 carried by a shaft 14, the latter shaft being fitted with tight and loose pulleys 15 and 16 and being provided with a hand wheel 17. A driving belt 18 operates 70 on the pulleys 15 or 16, the belt driving the gears when on the pulley 15 and running free when on the pulley 16.

The side of the drum remote from the shaft 8 is rotatably mounted on a shaft 19, 80 the outer end of which is carried by a carriage 20, the wheels 21 and 22 of which ride a horizontal curved track 23, the track being concentric to the post 3. The shaft 19 is tubular and receives a testing tube 24 85 which can be inserted within and withdrawn from the interior of the drum.

According to the above arrangement it will be obvious that the drum can be rotated around its horizontal axis and that the said 90 drum can be laterally shifted to change its position from that as shown in Figure 1 to a position above a plurality of gas or such like burners 25 located within a heating chamber 26. The drum receives the grain or 95 such like material to be treated when in the position shown in Figure 1 and in this connection it is explained that the grain is put into the drum through an overhead spout (not shown), one of the gates or doors being 100

brought to the top and opened to permit the passage of the grain into the drum.

After the grain is introduced and the gate has been closed the drum is swung laterally 5 into the heating chamber and is rotated by the belt and the grain or other material thereof is roasted while the drum is under the influence of the heat developed by the burners. After roasting, the drum is re- 10 turned to the original position and the contents thereof are dumped through one of the gates into a receiving pan or tank 27, located on the floor.

In order to withdraw moisture and other 15 floating material from the drum during the roasting operation, the drum is fitted with a pair of cylindrical screens 28 and 29 which open into the interior of the cap 7 and moisture and other floating material is 20 drawn from the drum by suction through the pipe 6. Interiortly the drum is fitted also with a vertically disposed and centrally positioned spider 30 which carries radially disposed equi plates 31.

25 The device as hereinbefore described is now in use and I have found that the grain or other material roasted within the drum is not evenly roasted and that there is unnecessary time lost as the grain or other 30 such material is not stirred to permit, not only of more effective roasting, but also of quicker roasting.

The wings which I provide are secured to the inner wall of the drum in any suitable 35 manner and are now described in detail.

One wing 32 has one end thereof positioned adjoining one side of the door 3 of the drum and the other end positioned adjoining the opposite side of the other door 40 2 and it passes circumferentially within one-half of the drum from side to side with the outer edge 33 thereof engaging the inner wall of the drum and the inner edge 34 thereof of clearing the outer edges of the plates 31.

45 The ends of the wing are fastened to the drum by angle brackets 35 and 36. The other wing 37 is similar to the wing 32 and passes circumferentially within the other side of the drum and has one end terminating adjoining the same side of the door 3 as the other wing, and the other end thereof terminating at the same side of the door 2 as does the other end of the other wing. Both wings are slightly inclined in respect 50 to the shell of the drum as best shown in Figure 2.

When the material is being roasted within the drum said drum rotates in a counter-sunk clock-wise direction, that is, in the direction indicated by the applied arrow in Figure 1 and the inclination of the wings is such that they incline slightly towards the direction of rotation. When the charge is in the drum and the same is being rotated above 60 the burners 25 the wings act to gather the

grain or such like material at the bottom of the drum and carry it up towards the top thereof, in the meantime stirring the same, and when the grain reaches the top it is thrown down on to the top of the grain lying 70 in the lower side of the drum. This action of the wings constantly stirs the grain so that the same is subjected to an even heat and there is no possibility of any of the grain being burned. The roasting is accomplished more evenly and thoroughly and can be done much quicker than in the old type 75 of drum where no such wings are used.

After the grain has been roasted and the drum has been turned back to its original 80 position above the tank 27, the contents thereof are discharged through one or other of the doors, the door being opened after the same has been brought to the bottom of the drum. During the discharging operation 85 the wings function further to aid in discharging the grain as they form interior chutes leading to the doors.

What I claim as my invention is:

1. In a roasting drum having diametrically opposing entrance doors, opposing wings extending inwardly from the inner wall of the drum and passing angularly thereacross. 90

2. In a spherical rotatably mounted roasting drum having diametrically opposing entrance doors, wings secured to the inner wall of the drum and passing thereacross in an angular direction with regard to the direction of rotation of the drum and having the 95 ends of the wings terminated adjoining the sides of the doors. 100

3. In a spherical roasting drum, said drum having the ends thereof rotatably mounted and being provided at the sides with diametrically opposing doors, a pair of wings secured to the inner wall of the drum, said wings being positioned to stir the contents 105 of the drum in the rotation thereof. 110

4. In a spherical roasting drum, said drum having the ends thereof rotatably mounted and being provided at the sides with diametrically opposing doors, a pair of wings secured to the inner wall of the drum and extending angularly thereacross and having the ends of the wings terminating adjacent the sides of the doors, the adjoining ends of both wings being positioned at the same side 115 of the doors. 120

5. In a spherical roasting drum, said drum having the ends thereof rotatably mounted and being provided at the sides with diametrically opposing doors, a wing passing around one-half of the interior of the drum from one side of one door to the opposite side 125 of the other door and a wing passing around the other half of the drum from the latter side of the latter door to the opposite side of the former door. 130

6. In a spherical roasting drum, said drum

having the ends thereof rotatably mounted and being provided at the sides with diametrically opposing doors, a wing passing around one-half of the interior of the drum 5 from one side of one door to the opposite side of the other door and a wing passing around the other half of the drum from the

latter side of the latter door to the opposite side of the former door, both of said wings being inclined in respect to the drum body. ¹⁰

Signed at Winnipeg, this 12th day of February, 1924.

WALTER JAMES RUSSELL.
